CENTRIFUGAL DEWATERING MACHINE

Frank R. Wassberg, Coleraine, Minn.

Application December 15, 1949, Serial No. 133,019

1. Claim. (Cl. 210—72)

1 This invention relates to a means for expelling excess or free moisture from moisture samples taken from washed iron ores.

The method of securing dependable moisture samples from iron ore shipments has been a serious problem and two general methods have been conventionally employed for many years, these being the moisture box and the car drainage methods. The moisture box is so constructed that a sample placed therein must be allowed to drain for approximately 24 hours. The difficulty arising from use of this method resides in the length of time required to calculate the moisture for grading purposes, and the possibility of contamination.

In the car drainage method railroad cars are allowed to drain a specified time, based on comparative tests made over a period of years. By this method the calculated moisture is obtained quickly with satisfactory results. However, difficulties are experienced when the time is shortened by the railroad company switching out the loaded cars before drainage is complete. Difficulties are further experienced when the ore is subjected to weather conditions during the drainage period.

It is an important object of the present invention to provide a means for taking moisture samples that will expel the water contained in said samples in excess, in minimum time.

Another important object is to provide a means of the type stated which will de-water the samples in such a manner as to permit the moisture content to be calculated with great accuracy.

An important object is to permit the calculation of the moisture content as soon as possible.

Another important object is to provide a machine of the type stated which will make it possible to make dependable moisture determinations on structure drill cuttings, which are invaluable in estimating the grades of unmined ore.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings

Fig. 1 is a front elevational view of a centrifuge 56 with the drawings.

2 de-watering machine constructed in accordance with the invention.

Fig. 2 is a side elevational view.

Fig. 3 is an enlarged vertical section through the upper end of the machine.

Fig. 4 is a section taken substantially on line 4—4 of Fig. 3.

Referring to the drawings in detail, an electric motor 5 is controlled by time switch 6 so that an attendant, after turning on the motor can proceed to other work without the necessity of paying attention to the machine during its operation. The motor 5 is mounted upon a bracket 7 supported by a cross bar 8 secured as at 9 to upwardly converging legs 10 and 11 of a supporting frame that also includes the rear leg 12, the legs 10, 11, and 12 converging upwardly and being secured at their upper ends to a vertically extending support 13 which can be formed from channel material, the lower end of said vertical support 13 being supported upon a horizontally extending support 14 which can also be a channel member, the ends of the horizontal support 14 being supported by feet 15 which can be bolted or otherwise secured to a supporting surface S. Extending rearwardly from the medial portion of the horizontal support 14 is the rearwardly extending horizontal supporting member 16 secured against movement by means of bolts 17 extending into the supporting surface S, the rear end of the member 16 being secured to and supported in elevated position by a foot 18.

Secured to and extended forwardly from the medial portion of the vertical support 13 is the lower bearing bracket 19. Thus collar 20 disposed above bushing 21 on the centrifuge shaft 22 journaled in the bearing, is disposed immediately above said lower bearing bracket 19, as best seen from Figs. 1 and 2. Below the lower bearing, a flexible flanged coupling 23 connects the lower end of the centrifuge shaft 22 to the motor shaft 24 of the electric motor 5.

Extended forwardly from the upper portion of the vertical support 13 is the upper bearing 25, and that portion of the centrifuge shaft 22 extending through said upper bearing is provided with the bushing 26.

Referring now to Fig. 3, the upper end of the centrifuge shaft 22 is extendable into a sleeve 27 having at its lower end the diametrically opposed slots 28 receiving cross pin 29 that extends through the centrifuge shaft 22. Thus, the sleeve 27 can be dropped upon the upper end of the shaft 22 and is thus keyed thereto for rotation with the shaft.

Rigid with the lower end of the sleeve 21, and extending upwardly therefrom, is the base portion 30 of inverted frusto-conical formation, this base portion increasing in diameter to its point of intersection with the upper portion 31 of the sample-receiving container or receptacle, the upper portion 31 or hood, being of frusto-conical formation and increasing downwardly in diameter to its point of intersection with the base portion 30 of said receptacle. At the point of intersection the receptacle is of course of greatest diameter, and at this point is provided with a circumferential series of openings 32 through which excess moisture can be expelled on operation of the centrifugal de-watering machine.

Water expelled through the openings 32 is driven into a cylindrical shield 34 the bottom of which is closed by frusto-conical skirt 35, so that said water must of necessity fall into an annular trough-like bottom provided in the shield, so as to drain through opening 36 in which is fitted one end of a drain hose 37. The receptacle for receiving the moisture sample extends through the opening 38 provided in the upper end of the frusto-conical bottom 35 of the shield. The frusto-conical skirt 35 is secured at its lower edge to the lower edge of the cylindrical shield 34, and extends upwardly to a location spaced substantially below the point of greatest diameter of the receptacle, intersecting with the base portion 30 of said receptacle intermediate opposite ends of the base portion, the skirt 35 being inclined oppositely to the base portion. The construction permits the base portion to be completely removable, while at the same time the receptacle and the shield are automatically centered and the entire structure held in exact alignment during operation, which is desirable to insure complete accuracy in operation for even distribution of water flowing through the several openings 32 and uniform release of said water into the shield so that proper drainage is assured through the drainage tube 37. In this connection, the frusto-conical skirt 35 intersects as before mentioned with the cylindrical shield at the bottom end, with the tube 37 opening from the bottom of the shield. The skirt 35 and shield 34 thus define an annular trough which at its lower end is of acute-angled cross-sectional configuration, with the drainage being at the bottom of the angle, thereby to insure complete drainage of all moisture from the shield.

The shield is rigid with a bracket 39 that is seated upon the upper end of the vertical support 13.

As will be seen from Fig. 3, the sleeve 21 extends upwardly within the lower portion of the base 30 of the receptacle, and accordingly, I provide a disc-like false bottom 33 in said receptacle, said false bottom 33 closing the upper end of the sleeve 21.

The operation of the machine will now be readily appreciated. The moisture sample, in an amount determined most practical by experience, is deposited upon the bottom 33 of the receptacle, after having been taken in the standard method from a plurality of car lots and crushed to minus $\frac{1}{4}$ inch mesh. The motor is turned on, and as previously noted, the operation of said motor is timed, so that the attendant need not remain at the machine during the de-watering of the sample.

From the results of many tests, experience shows that 25% of the excess water is expelled in one minute, and after two minutes, approxi-

mately 99%. From 2 to 10 minutes, very little change is noticeable and most of the wash ores tested showed that after 4 minutes practically all the excess water is driven out. A period of 7 has been adopted as standard for de-watering ores, in most instances.

After the water has been expelled, a selected portion of the sample is placed in a drying oven and dried at 212° Fahrenheit for 3 hours. The moisture percentage is then calculated.

The grading of iron ore becomes more complicated each year, because the various elements are now graded more closely to the guarantee than in former years, and it is very important that the iron natural content be calculated as soon as possible. It is important to secure proper moisture results, as experience has shown that different areas in one mine will vary materially in moisture.

It has been found that a machine constructed as illustrated and described herein is admirably suited for the purposes indicated, and it is now possible, where it has not previously been possible, to make dependable moisture determinations on structure drill printings, which are invaluable in estimating the grades of unmined ore.

In operation, it will be seen that the whirling of the centrifuge receptacle at high speed will cause the excess water to travel downwardly along the wall of the upper portion 31 of the receptacle, while water driven out of that part of the sample disposed within the lower portion 30 travels upwardly along the wall of said portion 30. All the water, whether travelling upwardly or downwardly, is eventually expelled through the single circumferential series of openings 32 and drained off.

Upon termination of machine operation, the centrifuge receptacle is simply lifted out of its seat 38 and off the end of the shaft 22, for further processing of the moisture sample. Other moisture samples are then deposited in the receptacle, and the receptacle returned to the position shown in Fig. 3, in which position it is ready for further de-watering of samples.

What is claimed is:

In a centrifugal ore dryer an elongated shaft mounted to rotate about a vertical axis, a prime mover, a flexible flanged connection between said prime mover and said shaft adjacent the lower end thereof for rapidly rotating said shaft, said shaft having a cross pin extending therethrough adjacent its upper end, an elongated sleeve removably mounted on the shaft in an encircling relation with the upper end thereof, said sleeve having diametrically opposed recesses opening through its lower end for receiving the cross pin and supporting the sleeve on the shaft for rotation therewith, an inverted frusto conical container carried by the sleeve for rotation therewith above the shaft, a frusto conical hood carried by the container and extending inwardly above said container, said hood cooperating with the container in confining ore to be dried, and the junction of said container and said hood having an annular series of peripherally spaced openings extending therethrough through which is discharged water removed by centrifugal force from ore in the container, an elongated shield surrounding the container and the hood in concentric spaced relation thereto, a frusto conical wall carried by the shield and extending inwardly and upwardly from the lower end of the shield to a plane intermediate the upper and lower ends of

5

the container to define with the shield an annular gutter in which is collected water which is discharged through the peripherally spaced openings.

FRANK R. WASSBERG.
